TIME CONTROL FOR REPOSITORIES

Charles F. Meilink, Toledo, Ohio

Application June 24, 1935, Serial No. 28,176

15 Claims. (Cl. 70—269)

This invention relates to protective mechanisms embodying safety provisions.

This invention has utility when incorporated in safeguards, especially of receptacles against unauthorized attack. Primarily there are features of locking, not only as effective for time delay against unlocking, but also indicate the unlocked or opened condition. This indication may be used for a bank teller's cage cash reserve as a signal for the cashier or other bank supervisor. Furthermore there is definite manual control selectively in sequence for further safeguarding, such as by signal to police or American District Telegraph.

15 Referring to the drawings:

Fig. 1 is a front view, with parts broken away, of an embodiment of the invention, say for a teller's cash receptacle;

20 Fig. 2 is a view of the inner side of the door for the receptacle of Fig. 1, the inner cover plate being broken away;

Fig. 3 is a section on the line III—III, Fig. 2;

25 Fig. 4 is a view of the tumbler lock device with the cover plate removed and the bolt unthrown or in full locking position;

Fig. 5 is a view similar to Fig. 4, with the bolt partially thrown, or in the first position of sequence for electric mechanism control;

30 Fig. 6 is a section on the line VI—VI, Fig. 4; and

Fig. 7 is a wiring diagram of the electrical mechanisms.

Floor 1 in a teller's cage need not be cluttered with burglar warning means. Receptacle 2 on such floor is provided with counter height top 3. The receptacle 2 has a vertical side opening 4, to one side of which are hinges 5, swingably mounted closure 6. Spindle 7 as rockable is effective through arm 8 to act on vertical bar 9 to shift such bar horizontally toward the hinges 5 and thus withdraw closure-releasing bolts or safe-guarding means 10. The door 6 is thus freed for opening.

45 On the inner side of the closure 6 (Fig. 2) is mounted lock box 11 having closure plate 12 removably attached thereto by bolts 13. Control of the locking devices through spindle 14 which is adjacent the spindle 7. Graduations 15 at the spindle 14 are guiding to the one knowing the combination for placing tumblers 16 to have notches 17 align. Lateral lug 18 from dog or pawl 19 may enter these notches 17 as the dog 19 swings on its pivot bearing 20. Pivot bearing 20 is in member 21. The member 21 is horizontally slideable in guides 22, 23, fixed with the lock box 11. Notch 24 on the lower side of the dog 19 thus comes down into the range of pin 25 on disk 26 fixed with the spindle 14. At the tumbler notch alignment as the predetermined unlocked posi-

tion, the dog of the locking device comes into the control of the operator of the spindle 14, and the slideable member 21 of this unlocker may be controllably moved. Arm 27, mounted by screw 28 in the box 11, is in position against a tumbler 16, and should there be attack attempt by forcing inward the spindle 14 and the disk 26, the arm 27 would be shifted about the screw 28 as a fulcrum. Nor would such attack bring the dog 19 into the notches 17 to permit movement of the member 21.

Bolts 29 in slots 30 of U-shaped bracket 31 permit close adjustment of this bracket 31 as to the member 21. Switch 32 is mounted by nuts 33 in this bracket adjustably to locate switch operating plunger 34 in position to be acted upon by plate 35 at the terminus of the member 21 remote from the spindle 14. Bolts 36 assemble this spring plate 35 with the bolt 21 to protrude therebelow.

Spring 37 acts upon the plunger 34 normally to thrust such plunger toward the member 21. Rather stiff spring terminus 38 for the lower portion of the plate 35 is curved away from the box 11. Accordingly, as the member 21 shifts into the box 11, this terminus 38 acts as a cam upon plunger 39 to thrust such against the action of its spring 40, and thus acts on second switch 41 mounted by nuts 42 in the lower arm of the bracket 31. Each switch is accordingly adjustable as to the bracket 31, and the bracket 31 is adjustable as to the box 11. Notch 43 in the lower side of the member 21 is engaged by tapered end of plunger 44 as yieldably urged by helical spring 45. This provides a yieldable resistance to the shifting of the member 21 as the switch 32 is operated and before the switch 41 has been actuated in sequence thereafter.

In normal operation, the plunger 44 is limited in its movement into the notch 43 by the arm 27. However, if the spindle 14 is driven in in an unauthorized attack, the arm 27, swinging on its fulcrum 28, is thrown clear of the shoulder on the bolt 44, thus allowing the spring 45 to move the bolt 44 into the notch 43 to lock the member 21 against movement.

Electrical features of safe-guarding are cooperative herein. Electric power supply lines 46, 47, extend to fitting or plug 48 (Fig. 7). From this fitting 48, the line 46 has connection by way of line 49 with fitting or plug 50, and therefrom by line 51 to the switch 32 as first in the sequence for action thereon by the member 21. From the switch 32 this line 51 has connection by way of line 52 to the fitting 50 independently of the line 49, thence by line 53 to the fitting 48 independently of the line 46, and therefrom by way of line 54 to electric mechanism 55, herein shown as a signal visible to the cashier or other bank supervisor for the teller or one whose duty it is

to handle the receptacle 2 for safety. From the fitting 48 and connected with the line 47 is line 56 to the electric bulb or signal 55. As the operator of the spindle 14 has the lock device in 5 predetermined assembly of the tumblers 16 to effect initial shifting of the member 21, there is safe-guarding warning of such condition at the mechanism 55. Should the operator be lax in not using the receptacle for protection, such 10 laxity is indicated at the light 55 for warning to the operator.

Closing of the switch 32 additionally connects the line 51 with line 57, extending to time delay mechanism in housing 58 (Fig. 2), herein shown 15 as mounted in the closure 6. Manually adjustable arm 59 is located as a predetermined time control or position on scale 60, and is there effective through adjustable arm conductor 61 from the line 57 to extend to line 62 and the synchronous 20 motor 63, circuit through which is completed by line 64 (Fig. 7) to fitting 50, line 65 to fitting 48, and there connected to the line 47.

Between the lines 51, 64, is coil 66. Closing of the switch 32 energizes the coil 66, which there- 25 by connects the transmission means 67 to be actuated by the motor 63. This operation of the transmission results in shifting of the pointer 68 along the scale 60. The pointer 68 is effective at adjustably located switch 69 to connect line 30 70 from the line 62 with line 71 extending to coil 72 connected by line 73 with the line 64. The coil 72 is thus placed in parallel with the motor timer 63 as such motor is still running and the gearing means 67 is clutched, for an effective 35 current to be taken by the coil 72 operative to withdraw bolt or release 74 (Figs. 2, 3, 7) from holding position as to the bolt 10, thereby allowing the spindle 7 to function in operating the bolts 10 to release position.

40 Spring 75 is effective at de-energized condition of the coil 72 to hold the bolt 74 against the side of the bolt 10. It thus follows that any throwing of the bolts 10 to locking position when the current is not energizing the coil 72, allows 45 the bolt 74 to come to effective locking position to keep such bolts 10 thrown.

By releasing latch 76 (Fig. 2), closure plate 11 may be swung downward, and the arm 59 reset for a desired subsequent time-delay or lag in 50 permitting opening of the closure. The member 21 does not permit its release to be forthwith operable until the electric motor mechanism of the synchronous motor 63 has run its cycle as predetermined in the manual setting of the arm 59 55 as to the scale 60. When there has elapsed the timed release so that the coil 72 is energized, then the bolt 74 may be withdrawn to permit operation of the spindle 7 and withdrawal of the bolts 10.

60 By placing the electric signal mechanism 55 in parallel with the time delay mechanism 58, there is effective inter-relation brought about by the three lines from the fittings 48, 50, or both thereof, of safe-guarding value herein for 65 delay, or immediacy of the remote signal, for the function be definite as brought about by the functioning of the mechanism 58.

While there are two fittings 48, 50, and two mechanisms 55, 58, additionally there are two 70 mechanisms at the bolt 21, the switch 32, and the switch 41. Lines 78, 79, from the switch 41 extend to plug or fitting 80 (Fig. 7) adjacent the fitting 50 (Fig. 2) as mounted in the closure 6. Lines 81, 82, from the fitting 80 extend to fitting 75 83 in outlet box 84 adjacent the fitting 48 (Figs.

1, 7). The box 84 may be on wall 85 and remotely therefrom is located police warning or mechanism 86, connected by lines 87, 88, with the fitting 83. The line 87 is connected to power line 47. The line 88 is connected to coil 89 and has its circuit therefrom completed by line 90 to the electric current supply line 46. Switch 41 as normally closed has the coil 89 energized to keep switch 91 open. As the switch 41 is opened, the coil 89 is de-energized; the switch 91 closes. Energy source or battery 92 has line 93 therefrom to the switch 91, which switch as closed connects by line 94 to signal or alarm 95 as a warning mechanism with the circuit therefrom completed by line 96 to the battery 92. 10 This electric mechanism is self-resetting as the bolt 21 is shifted toward unthrown position or toward the switch 32, thereby permitting the switch 41 to close switch 91. Switch 97 in the line 90 may be operated manually from time to time for thereby opening and closing the circuit including the coil 89 when the switch 41 is closed. Then with the coil 89 energized the alarm 95 should be sounded.

Fixed with the arm 68 on shaft 97' is cam 98 effective as the continued operation of the motor 63 shifts the arm 59 and the closed switch 69, further to move the cam 98. This cam 98 is accordingly a motor actuated control effective after a time interval following the closing of the switch 69 to act on switch 99 as a stop in opening the circuit in the line 57. The arm 68 may have been set or reset manually to run say fifteen minutes to close the control part or switch 69. The cam 98 may be adjusted to act upon the switch 99 in say three minutes after the switch 69 was closed. This means that as the switch 99 is opened the motor 63 stops, the coil 72 is de-energized so that the bolt 74 is again thrown to locking position by the spring 15, and the coil 66 is de-energized to unclutch the motor 63 from driving the arm 68 through the differential or speed reduction gearing 67. Torsion spring 100 on the shaft 97 is then at once effective to reset the arm 68 as the bolt 74 is returned to locking position.

When the door 6 is open, pin 101 (Fig. 3) from the bolt 74 projects through opening 102 in rear cover plate 103 for the door 6. The attendant may manually release the spindle 7 by operating the pin 101 to hold the bolt 74 against the action of the spring 75.

When the door 6 is open, switch 104 (Figs. 2, 7) between the lines 51, 52, is closed, thereby giving warning signal at the light 55. When the spindle 7 is at bolt unlocking position, switch 105 is in closed position between the lines 51, 52, also serving to light up the signal 55. Therefore, at any time when the time delay mechanism is operated, if there be opening action, it is signaled should there be unsafeguarded condition as through open door 6 or as through locking bolts 10. If the door be closed and the bolts not withdrawn, the cam 98 is effective to relock the mechanism.

What is claimed and it is desired to secure by United States Letters Patent is:

1. Receptacle safe-guarding means, in combination with a lock device including a movable member, a control for the device to effect shifting of the member, a synchronous motor timer, a circuit from the timer to the member, a switch operable by the member to control the timer, from said circuit additional circuit means controlled by the timer, and an electrically actuatable re-

- lease for the safeguarding means, said additional circuit means being for the release and delayed by the time.
2. For a receptacle provided with a safeguarding closure, a lock device including a slidable member controllably positioned by the lock, an electric motor, a part to be driven by the motor and connectible for such driving by the positioning of the member, a control part for the motor, 5 bolt means connected to be actuated by the control part, a manually controllable reset for the parts relatively to each other, and a time adjustment for delaying operation of the control part to effect actuation of the bolt means.
3. For a receptacle provided with a safeguarding closure, a lock device including a slidable bolt controllably positioned by the lock, an electric motor for the device, a part to be driven by the 10 motor and connectible for such driving by the positioning of the bolt, a control part for the motor, primary locking means for the closure, a release for the primary locking means connected to be actuated by the control part, and a manually controllable reset for the parts relatively to 15 each other independently of said bolt.
4. For a receptacle provided with a safeguarding closure, a lock device including tumbler mechanism, a bolt shiftable upon predetermined operation of the mechanism, protective electric 20 motor mechanism, an electric circuit therefor, said protective electric motor mechanism including a time set electric motor, a switch in said circuit operable by shifting of the bolt to start the motor, primary locking means for the closure, 25 and a release actuatable through the motor mechanism for the primary locking means.
5. For a receptacle provided with a safeguarding closure, a locking device including tumbler mechanism, a bolt connected to be shifted upon predetermined operation of the mechanism, primary locking means for the closure, a release for the primary locking means, a switch operable by the bolt, electric motor mechanism responsive to such operation of the bolt, and a circuit including 30 said motor, switch and release.
6. For a receptacle provided with a closure, a tumbler lock device, a bolt shiftable from the device, primary locking means for the closure, a release for the primary locking means, time delay primary protection mechanism operable by the bolt for rendering the release effective, and relatively movable supplemental protection-providing means at the device in addition to said mechanism and apart from said bolt, shiftable in 35 response to said bolt independent of said mechanism.
7. For a receptacle provided with a closure, a tumbler lock device including a relatively shiftable member, primary locking means for the closure, a release for the primary locking means, first and second electric-protection providing 40 mechanisms independently responsive to shifting of said member, one of said mechanisms being acted upon by the member to render the release effective, the other mechanism including a switch to cut out said one mechanism.
8. For a receptacle provided with a closure, a tumbler lock device including a bolt, primary locking means for the closure, a release for the primary locking means, first electric mechanism including a first switch actuatable by the bolt, and second electric mechanism including a second switch actuatable by the bolt apart from the first switch, said mechanisms being independently 45
- operable protective means and one thereof including time delay means brought into action by said bolt operable for rendering the release effective.
9. A safety device including a lock, electrical mechanism connected therefrom embodying protective means including a switch coacting with the lock to be actuated thereby, control mechanism for the device cut in by said switch operation, and additional switch means operable 5 by the control mechanism to cut out operation of the electrical mechanism.
10. For a receptacle provided with a safeguarding closure, locking mechanism including a control device, primary locking means for the closure, a release for the primary locking means freed for functioning in response to said device, and electrically actuatable protective means embodying a circuit from the mechanism and having a switch cooperating in said circuit and operable from the device in addition to said release.
11. For a receptacle provided with a safeguarding locking mechanism including a control device, a switch for the device, primary locking means for the closure, a release for the primary locking means freed for functioning in response to said device, and electrically actuatable protective means, a circuit from the mechanism, and an additional switch cooperating in said circuit and operable from the device in addition to said release.
12. For a receptacle provided with a closure, a tumbler lock device, a first housing for the device, electric means including a switch for the device, a bolt shiftable from the device to operate the switch, primary locking means for the closure, a release for the primary locking means, time delay synchronous electric motor mechanism operable by the switch for rendering the release effective after an interval, and a secondary housing for the mechanism to which the electrical means extend from the first housing.
13. For a receptacle provided with a safeguarding closure, a locking device, primary locking means for the closure, and for cooperation in protecting said receptacle, electric circuit means to the device including a switch connected to be actuated from the closure as released by the primary locking means.
14. For a receptacle provided with a safeguarding closure, a locking device, primary locking means for the closure, a release for the primary locking means, electric mechanism operable from the device for rendering the release free for functioning, and for cooperation in protecting said receptacle, electric circuit means to the device including a switch connected to be actuated from the locking means.
15. For a receptacle provided with a safeguarding closure, protective mechanism between the mechanism and closure embodying a lock device including a pawl, a bolt on which the pawl is mounted for shifting on predetermined operation of the device, an electric motor operable 60 for effecting control of the mechanism, a circuit for the motor, a switch in said circuit operable by shifting of the bolt, a stop for the motor rendering the switch inactive, primary locking means for the closure, a release to shift the primary locking means relatively to the closure, and a control connected to be actuated by the motor to operate the stop and the release.
